UNITED STATES PATENT OFFICE.

LEO STEINSCHNEIDER, OF BRÜNN, AUSTRIA-HUNGARY, ASSIGNOR OF ONE-THIRD TO
PHILIPP PORGES, OF VIENNA, AUSTRIA-HUNGARY, AND ONE-THIRD TO RICHARD
NEUMANN, OF BRÜNN, AUSTRIA-HUNGARY.

APPARATUS FOR DISTILLING PETROLEUM, TAR, OR OTHER SUBSTANCES UNDER VACUUM.

1,192,581.

Specification of Letters Patent. Patented July 25, 1916.

Application filed October 8, 1914. Serial No. 865,632.

To all whom it may concern:

Be it known that I, LEO STEINSCHNEIDER, engineer, a subject of the Emperor of Austria-Hungary, residing at Franzensglacis 1, 5 Brünn, in the Empire of Austria-Hungary, have invented a new and useful Apparatus for Distilling Petroleum, Tar, or other Substances Under Vacuum, of which the following is a specification.

- 10 One of the most important requirements in the distillation of oils of the petroleum, tar, or other industry under vacuum, is to be able to continuously and systematically inspect or examine the products of the distillation. For this purpose it is desirable that 15 the condensates shall issue freely and visibly into the atmosphere, without however involving a breaking of the vacuum in the still or generating chamber.
- 20 Heretofore, in distilling under vacuum the condensates are usually allowed to flow through a valve-controlled pipe, into a receiver also under vacuum. When the receiver is full, the valve in the inflow pipe is 25 closed and the vacuum in the receiver is broken by the admission of air. The condensate may then be drawn from the receiver through a suitable outlet. When empty, this receiver may again be placed 30 under vacuum, and the condensate again allowed to flow into the same. Since these receivers are rather large, and take considerable time to be filled (one or more hours) it is only possible to examine the condensate 35 at the ends of rather lengthy periods.
- The object of the present invention is to enable the condensate to be examined at much shorter and regular intervals, by admitting the condensate at frequent and regular intervals into a smaller receiving chamber, and discharging the condensate at correspondingly frequent and regular intervals, irrespective of the receiving chamber being full or only partly full. This object 40 may be attained by a regular mechanical actuation of the admission and discharge valves of the receiver, so that the condensate may be examined at desired intervals, for instance, of a minute each.
- 45 In the drawings which illustrate several forms of the improved apparatus for carrying the invention into effect, Figure 1 illustrates one embodiment of the improved ap-

paratus, and Figs. 2-4 show modifications of the device V shown in Fig. 1.

In Fig. 1, A designates the still, K the water cooled condenser, and C another condenser for receiving the uncondensed gases from the condenser K, all of which operate under vacuum.

V is an improved receiver.

R is the collecting vessel, into which the condensates flow from the receiver in a visible manner.

F is a vacuum pump and 11 Fig. 1 an exhaust pipe through which uncondensable gases drawn from the condenser C through the pipe 12 are passed off.

The condensate coming from the condenser K flows through the pipe 1 into the chamber 2 of the receiver V. By means of an actuating lever Q or other suitable mechanism, which is preferably power-operated, a valve 3 in the receiver V is opened, allowing the condensate in the chamber 2 of the receiver to flow into the chamber 4. After an interval of desired or predetermined duration the valve 5 is opened and the valve 3 closed by a spring or the like, whereupon the condensate can flow through the 80 adjustable siphon S in a visible manner into the collecting vessel R where it may be suitably inspected or examined. During this outflow, fresh condensate collects in the chamber 2 and the operations proceed cyclically. Portions of the condensate will thus 85 pass regularly and at desired intervals into the atmosphere. In the chamber 4 there is vacuum during one period of working, at atmospheric pressure during the following 90 period of working.

The extent to which the chamber 4 is filled with condensate during one working interval depends on the amount of condensed vapor which has passed over from the still in the said interval. Each time after emptying, the entire free space in chamber 4 will become filled with air, and this air must be drawn off by the air pump during the next working interval. For the 100 purpose of making the quantity of air which has to be sucked away as small as possible, it is advisable to make the free space in the chamber 4 as small as possible, i. e., only so large as will enable it to just hold the 105 flowing amount of condensate at any par-

ticular stage of the distillation. Now, the amount of condensate varies considerably in the several stages of the distillation, so that it is advisable to make the capacity 5 of the receiving chamber 4 variable. This may be effected by a siphon S capable of being adjusted vertically. By screwing the part I higher or lower, the level *t* to which the chamber 4 can be emptied may be adjusted. Accordingly, the capacity of the chamber 4 above the level *t* may be adjusted to the inflowing quantity of condensate.

For the purpose of facilitating the opening of the valves 3 and 5 or other controlling devices, the arrangement may be so modified that before either the valve 3 or 5 is opened, equal pressures will be established on both sides thereof. As shown in Fig. 3, auxiliary valves 6 and 7 are provided, the valve 6 being connected by a pipe 8 with a vacuum condenser C or the suction tube 12 of the air pump P, and the valve 7 being connected with the atmosphere.

The controlling mechanism Q before opening the valve 3 opens the valve 6, the valve 7 controlling the passage to the atmosphere 25 and the outlet valve 5 remaining closed; by this means the chamber 4 is placed under vacuum. The valve 3 is now opened. The condensate flows as hereinbefore described, 30 from the chamber 2 into the chamber 4; the further operation of the controlling mechanism Q acts to allow first the valve 3 and then the valve 7 to close. Then the valve 7 35 leading to the atmosphere is opened, after which the valve 5 is opened, the chamber 4 being put under atmospheric pressure prior to the opening of the valve 5 by the valve 7. Upon opening of the valve 5 the condensate 40 flows out of the chamber 4 of the receiver.

A simpler arrangement, which is useful in special cases, is illustrated in Fig. 2, wherein the control mechanism is limited to controlling two auxiliary air valves 6 and 7. 45 The condensate passes at 1 from the condenser K into the chamber 2; valve 3 is closed by means of a spring and pressure in the chamber 4, when vacuum exists in the chamber 2 and atmospheric or partial atmospheric pressure in the chamber 4. If the auxiliary valve 6, which is connected by a pipe 50 8 to the vacuum chambers (condenser C or the suction pipe 12 of the pump P) is opened by means of the external controlling mechanism, for example, by means of an eccentric E, then the chamber 4 will be placed under vacuum, the valve 7 remaining closed and the valve 5 closing. The valve 3 will now open under the hydrostatic pressure of the 55 condensate that has collected above it, and this condensate will flow into the chamber 4. Thereupon the mechanism is reversed, i. e., the valve 6 is closed and the valve 7 which communicates with the atmosphere, is 60 opened. Thereupon the chamber 4 is put 65

into communication with the atmosphere and the valve 3 is closed by the atmospheric pressure, since the chamber 2 is under vacuum. The valve 5 opens under the hydrostatic pressure of the condensate which has collected in 4, and the condensate can now pass into the atmosphere through the siphon T. Thereupon the operations are repeated, that is to say, valve 7 is closed, valve 6 is opened, valve 5 is closed, and so on.

If in a distillation plant there are a plurality of retorts and coolers with several outlets for the condensate, it will be sufficient at each outlet to provide only the chambers 2 and 4 with the valves 3 and 5, and to provide for all the outlets or retorts common valves 6 and 7, operated by an eccentric E¹ as shown in Fig. 4. The valve 6 is connected to the suction side (suction pipe 12) of the vacuum pump by means of a pipe 8, and the valve 7 is connected to the atmosphere. From this apparatus a connecting pipe 10 leads to each of the separate chambers 4 (for example, at a, Fig. 2). The valves 6 and 7 are alternately opened and closed by means of the eccentric E¹, so that the receiving chambers 4 are alternately placed under vacuum or under atmospheric pressure.

If the construction shown in Fig. 3 is to be used, then the valves 6 and 7 may be omitted therefrom and be replaced by the common apparatus, as shown in Fig. 4, connected by the pipe 10 to each of the separate chambers 4 (for example, at a Fig. 3).

If, in order to establish the atmospheric pressure in the chambers 4, it is not desired to admit air, then, instead of this air, for example, the uncondensed gases in the condenser C may be used, by connecting the valves 7 by means of pipes 9 to the exhaust pipe 11 of the air pump (Fig. 1) wherein atmospheric pressure exists and through which the gases escape.

What is claimed is:

1. A vacuum distilling device comprising a receiver for distillates, said receiver being of relatively small capacity and having an inlet for the incoming fluid and an outlet for the outgoing fluid, pressure reducing means, and means for periodically at relatively short intervals opening and closing said inlet and outlet for governing the action of said pressure reducing means upon said receiver.

2. A vacuum distilling device comprising a receiver for distillates having an inlet and an outlet, said receiver being of relatively small capacity, auxiliary openings, positively actuated means for periodically at relatively short intervals opening and closing said auxiliary openings, a vacuum pump, the inlet and exhaust sides thereof being alternately brought in communication with the auxiliary openings to establish vacuum and pressure in the receiver, the vacuum

being established prior to the opening of the inlet and the pressure being established prior to the opening of the outlet.

3. A vacuum distilling device comprising a receiver for distillates, said receiver being of relatively small capacity and having an inlet for the incoming fluid and an outlet for the outgoing fluid, an opening in communication with pressure reducing means, and an opening communicating with a medium adapted to establish atmospheric pressure, and means for opening and closing said inlet and outlet and said openings, said means operating to periodically at relatively short intervals open and close said inlet and outlet, and, in conjunction therewith, to open and close said openings in communication with the pressure reducing means and the zone at atmospheric pressure.

20 4. A vacuum distilling device comprising a receiver for distillates, said receiver being of relatively small capacity and having an inlet for the incoming fluid and an outlet for the outgoing fluid, an opening in communication with pressure reducing means, and an opening communicating with a medium adapted to establish atmospheric pressure, and means for opening and closing said inlet and outlet and said openings, said 25 means operating to periodically at relatively short intervals open and close said inlet and outlet, and, in conjunction therewith, to open and close said openings in communication with the pressure reducing means and the zone at atmospheric pressure, and said 30 controlling means operating to place said receiver in communication with a pressure reducing means prior to the opening of the inlet, and being adapted to establish substantially atmospheric pressure in the receiver prior to the opening of said outlet.

35 5. A vacuum distilling device comprising a receiver for distillates having an inlet valve for the incoming fluid and an outlet valve for the outgoing fluid, means for opening said inlet and outlet, and a vacuum pump adapted to have the inlet and exhaust sides thereof alternately in communication with said receiver.

50 6. A vacuum distilling device comprising a receiver for distillates, said receiver being of relatively small capacity and having an inlet valve for the incoming fluid and an outlet valve for the outgoing fluid and positively 55 acting mechanism adapted to regularly operate said valves at relatively short intervals independently of the progress of the distillation.

7. A vacuum distilling device comprising a receiver for distillates having an inlet valve for the incoming fluid and an outlet valve for the outgoing fluid and positively acting mechanism adapted to regularly operate said valves at relatively short intervals independently of the progress of the distil-

lation, the said receiver having auxiliary valves through which the pressure in said receiver may be alternately changed, said actuating mechanism operating one auxiliary valve to establish a vacuum in the receiving chamber prior to the opening of the inlet valve and operating the other auxiliary valve to establish atmospheric pressure prior to the opening of the outlet valve.

8. A vacuum distilling device comprising a receiver for distillates, said receiver being of relatively small capacity and having an inlet valve for the incoming fluid and an outlet valve for the outgoing fluid, positively actuated auxiliary valves operating to establish vacuum and atmospheric pressure in the receiver, at relatively short intervals, the inlet and outlet being closed by the vacuum and pressure alternately established by the auxiliary valves, and opened by the hydrostatic pressure of the distillates collected above the inlet and outlet.

9. A vacuum distilling device comprising a receiver for distillates, said receiver being of relatively small capacity and having an inlet valve for the incoming fluid and an outlet valve for the outgoing fluid and positively acting mechanism adapted to regularly operate said valves at relatively short intervals independently of the progress of the distillation, said receiver having a capacity substantially equal to the amount of distillates which collect during the interval in which the receiver is closed.

10. A vacuum distilling device comprising a plurality of receivers for distillates having inlets and outlets, a chamber common to all receivers having auxiliary openings therein, positively actuated means for opening and closing said auxiliary openings, said openings operating to establish alternately vacuum and pressure simultaneously in all the receivers, the vacuum being established prior to the opening of the inlets and the pressure being established prior to the opening of the outlets.

11. A vacuum distilling device comprising a plurality of receivers for distillates having inlet valves for the incoming fluid and outlet valves for the outgoing fluid, two positively actuated auxiliary valves and pipes connecting the valves to each receiver, said valves being actuated at relatively short intervals, one of said auxiliary valves operating to establish a vacuum simultaneously in all the receivers prior to the opening of the inlet valves and the other auxiliary valve serving to simultaneously establish atmospheric pressure in all the receivers before the outlet valve for the distillate is opened.

12. A vacuum distilling device comprising a receiver for distillates having an inlet and outlet, a vacuum device, and a collecting vessel, means for alternately opening the inlet and outlet at relatively short intervals

and bringing the receiver alternately in communication with the vacuum device and with the collecting vessel, the capacity of the receiving chamber being adjustable to the amount of the inflowing quantity of distillates.

13. A vacuum distilling device comprising a receiver for distillates having an inlet and outlet, a vacuum pump, and a collecting vessel, means for alternately opening the inlet and outlet at relatively short intervals and bringing the receiver alternately in communication with the vacuum pump and with

the collecting vessel, the exhaust side of the pump, which carries off the uncondensable 15 gases of the distillation, being in connection with the receiver to employ the exhaust gases of the pump, instead of air, to establish pressure in the receiver.

In witness whereof, I have hereunto 20 signed my name in the presence of two subscribing witnesses.
